INVERTER AND DISTORTER FOR SECRET
COMMUNICATIONS

Leonide E. Gabrilovitch, New York, N. Y.

Application January 13, 1945, Serial No. 572,693

15 Claims. (Cl. 179—1.5)

1

My invention relates to inverters and distorters for secret radio or telephonic communications and has particular reference to devices for distorting speech by "inversion" for rendering the speech unintelligible until it is reinverted at a receiving point.

As is known in the art, "inversion" consists in modulating the speech frequency band to be transmitted, on an oscillation whose frequency is beyond the upper limit of the particular speech band but very close to this upper limit, and in filtering out the upper side band of the thus formed modulated wave so as to maintain only the lower side band. It can be readily realized that this lower side band is located in the same frequency range as the initial speech band, but that all the frequencies of which this initial band is constituted, are "inverted," so that in any pair of such frequencies the upper frequency becomes the lower one and, inversely, the lower frequency becomes the upper one.

An "inverted" speech band is completely unintelligible. However, it can be easily "reinverted," i. e. re-transformed into the original speech band. This result is obtained by modulating the inverted band on an oscillation having substantially the same frequency as that used previously for effecting the inversion of the initial speech band, and by suppressing (by means of low-pass filtering) the upper sideband of the thus produced modulated wave. The original speech band is thus restored.

It is obvious that any unauthorized and undesired listener can perform such a reinversion by using very simple and handy arrangements. He can for example, convey the received "inverted" speech band to a balanced modulator which is at the same time acted upon by the output of a local oscillator whose frequency can be varied in a continuous way. The output of the balance modulator is conveyed through a low-pass filter whose characteristics can be changed in such a way that at any given moment this filter substantially weakens any oscillation whose frequency exceeds that of the local oscillator used.

The adjusting operation to be effected by the undesired listener consists in turning in a continuous way the dial controlling the frequency of the local oscillator (and at the same time, the "tuning" of the low-pass filter) until the received chaotic plurality of sounds is transformed into intelligible speech. This result can be in most cases obtained in a few seconds, so that inversion does not actually secure either secrecy or privacy.

The main object of my invention is to provide means and methods to render the speech band

2

unintelligible by an independent factor, with or without the preliminary inversion of the speech band. I provide for this purpose an arrangement whereby the speech band, either inverted or straight, is modulated by a sequence of harmonically related low frequencies thereby rendering the speech completely unintelligible. I further provide means to reestablish the intelligibility at the reception end by modulating the thus distorted speech band with the fundamental of the foregoing sequence of harmonically related frequencies, this fundamental being used in a proper phase relationship.

A further object of my invention is to provide means and methods to vary the phases of the modulated speech frequencies contained in a speech band in accordance with a predetermined pattern so that no demodulation can be obtained unless a demodulating oscillation is used whose phase undergoes exactly the same variations.

Still another object of my invention is to provide means and method to vary the phases of a particular speech band by modulating this band by a sequence of phase-varied oscillations, i. e. by a sequence of oscillation whose phase is made to vary periodically in accordance with a certain law.

Still another object of my invention is to provide means and method for periodically shifting frequencies of the speech bands by heterodyning them by frequency-varied oscillations whose frequency is made to vary, for instance, with the aid of frequency-varying means employed in the frequency modulation.

In a preferred (although purely illustrative) form the invention may be carried out in the following way:

Let it be assumed that the frequencies constituting the speech-band to be transmitted, range from 300 cycles to 3,000 cycles. This speech band is made to modulate a special "heterodyning" oscillation having a frequency located e. g. somewhere between 3,000 and 3,200 cycles. If the upper sideband of the thus produced modulated current is suppressed by low-pass filtering so that only the lower sideband is maintained, the initial speech band will be inverted. If the frequencies forming the original speech band are designated by the symbol f_h (wherein "h" is an index), the frequencies constituting the above mentioned lower sideband will have the form e. g.

3000— f_h

or

3200— f_h

In order to prevent the unauthorized or unde-

sired listener to reinvert the thus inverted speech band and to obtain in this way a partial or full intelligibility, the inverted speech band is modulated by a sequence of harmonically related low frequencies, for example by a fundamental having a frequency of 50 cycles and by 8 of its lowest odd harmonics.

Let us assume that the fundamental has a frequency of 50 cycles, so that the symbol α is defined in the equation:

$$\alpha = 2\pi \cdot 50$$

Under those conditions the inverted and distorted speech band will have the following analytical expression:

$$E_s \sin 2\pi(3000 - f_h) \cdot (\cos \alpha t + \cos 3\alpha t + \dots \cos 15\alpha t)$$

This inverted and distorted band will be evidently unintelligible since the original speech is not only inverted but also modulated by 8 harmonically related frequencies, the highest of which reaches 750 cycles.

It will be difficult, if not impossible, to "unravel" the thus distorted message by submitting it to a rectifying operation or to a "scanning heterodyning" (that is to say by modulating it with an oscillation whose frequency undergoes a continuous variation). In fact, if a simple rectifying operation is used, so that no independent carrier frequencies are admixed to the aggregate constituting the distorted speech, the product of said rectifying operation will consist substantially of the square term having the following analytical form:

$$[E_s \sin 2\pi(3000 - f_h)]^2 (\cos \alpha t + \cos 3\alpha t + \dots \cos 15\alpha t)^2$$

It can be readily figured out that under those conditions the proportion of the noise level to the signal level will be such that the product of this operation will remain unintelligible, even after being reinverted.

If "scanning heterodyning" is used, the proportion of the noise level to the signal level will still have a very high value so that substantially no intelligibility will be obtained.

At the reception end the inverted and distorted speech is modulated by the fundamental of the sequence of distorting frequencies used at the transmission end. This method is based on the fact that if the sum of harmonically related oscillations:

$$(\cos \alpha t + \cos 3\alpha t + \dots \cos 15\alpha t)$$

is modulated by the fundamental:

$$\sin \alpha t$$

the above-mentioned sum is transformed into a single oscillation whose frequency will be equal to the sum of that of the highest term of the sequence used and of that of the fundamental:

$$\begin{aligned} \sin \alpha t (\cos \alpha t + \cos 3\alpha t + \cos 5\alpha t + \dots \cos 15\alpha t) = \\ \frac{1}{2} \sin 2\alpha t - \frac{1}{2} \sin 2\alpha t + \frac{1}{2} \sin 4\alpha t - \frac{1}{2} \sin 4\alpha t + \\ \dots \frac{1}{2} \sin 16\alpha t - \frac{1}{2} \sin 16\alpha t \end{aligned}$$

My invention is more fully explained in the accompanying specification and drawing in which:

Fig. 1 is a diagrammatic view of a transmitter in which my method of distorting the speech is employed; and

Fig. 2 is a similar view of a receiver in which the transmitted distorted speech is rendered intelligible.

Referring to Fig. 1, the speech is received by a microphone 1 whose electric output is conveyed through a band pass filter 2 which selects frequencies within a limited range, for instance, from 300 to 2700 cycles. This speech band is made to modulate a special "heterodyning" oscillation having a frequency, for instance, 2700 cycles, which may be, however, even 3000 to 3200 cycles. This modulation is effected by a balanced modulator 3, receiving the foregoing heterodyning oscillation from a selector 9. This oscillation is a harmonic of the output of an oscillator 6 whose frequency can be varied for instance, between 10 and 25 cycles, which output is passed through a clipper 7 wherein it is transformed into a square wave.

The output of the balanced modulator 3 is fed to a low pass filter 4 having its cut off, for instance, at 2400 cycles. The modulator 3 and filter 4 are designed to invert the speechband with the help of the inverting oscillation of approximately 2700 cycles, provided by the selector 9.

The output of the filter 4 constitutes the inverted speech band and is fed to a double balanced modulator 5 in which the speech band is modulated by a sequence of phase-varied oscillations from an electronic switch 13. The latter is fed from two of the three parallel channels into which the output of the clipper 7 is divided. One of these channels comprises a low pass filter 8, having its cut off at approximately 800 cycles. The output of this filter will be evidently constituted by the output of the oscillator 6 and by seven of its lowest odd harmonics up to the fifteenth, the amplitudes of these harmonics being inversely proportional to their ranks. This output is fed to an equalizing amplifier 11 which equalizes the amplitudes of all the 8 oscillations of the filter 8. This amplifier may comprise, for instance, a pentode having a high internal resistance, and an appropriately designed coil inserted in the plate circuit of the pentode. Such an amplifier, in addition to its function of equalizing the amplitudes will also shift the initial phase of the 8 oscillations by approximately 90°.

The output of the equalizing amplifier 11 is divided into two parallel channels, one of which comprises a fixed phase shifter 12 dephasing by approximately 90°, any oscillation whose frequency is located between, for instance, 50 and 750 cycles. The output of this channel is fed to the electronic switch 13. The other channel is fed directly to this switch.

The third channel from the clipper 7 passes through a selector 10 which provides the oscillation synchronizing the electronic switch 13. By changing the tuning of the selector 10, it is easy to change the frequency of the phase variations of the eight distorting oscillations.

The inverted and distorted speech band is then fed to the high frequency modulator 14 of the radio transmitter.

The low frequency oscillation generated in the transmitter by the low frequency oscillator 6 is transmitted to the receiver, for instance, in the form of a modulation impressed on a special sub-carrier, which is provided, for example, by a conventional audio oscillator (not shown), whose frequency is located within a range of 3800-4000 cycles. In spite of the attenuation which this modulated sub-carrier may undergo due to the action of the input band-pass filter of the particular radio transmitter, this sub-carrier can be easily separated from the signal band by simple high pass filtering.

The receiver as shown in Fig. 2 comprises a low pass filter 15 having its cut-off approximately at 3500 cycles. This filter suppresses the sub-carrier while maintaining the whole signal band, which consists of the inverted speech modulated by the sequence of harmonically related low frequencies. This band is fed to a modulator 16 wherein it is modulated by the phase-varied fundamental of the foregoing sequence. As was mentioned, this modulating operation transforms a distorting modulation produced by a group of harmonically related frequencies into a modulation by a single frequency which is equal to the sum of that of the fundamental and that of the highest harmonic employed. It has been assumed that the fundamental of the distorting sequence has a frequency of 50 cycles and that seven odd harmonics are used, so that the highest harmonic (the fifteenth) has a frequency of 750 cycles. This means that the output of the modulator 16 will be constituted by the inverted speech modulated by a single frequency of 800 cycles.

The output of the modulator 16 is fed to a demodulator 17 and low pass filter 18, which provide a non-modulated inverted speech which is then reinverted in a conventional reinverter 19.

The lower row (reference characters 20 to 31) represents an arrangement designed to provide the phase varied modulating and demodulating oscillations to be applied to modulator 16 and to demodulator 17. 20 is a high pass filter which selects the special subcarrier on which is impressed the frequency standard. This standard is detected by a detector 21 and then fed to a clipper 22 to be transformed into a square wave.

The output of clipper 22 is divided into two channels. One of them contains a selector 23 selecting the oscillation used as fundamental of the distorting sequence. This oscillation is fed to the electronic switch 26 through two parallel channels, one of which contains a fixed phase shifter 25, shifting the phase of the incoming fundamental by 90°. The other channel is fed directly to the electronic switch 26. The electronic switch is synchronized by an oscillation picked up by a selector 24, which oscillation is identical to that provided in the transmitter by the selector 10 (see Figure 1). The output of the electronic switch is divided into two channels. One of them is directly fed to the modulator 16, the second is conveyed to a shape distorter 27 distorting the shape of a sine wave in such a way, that there appear all the harmonics of said wave (odd as well as even). A selector 28 picks up a determined harmonic, in our case, the sixteenth, which is conveyed to a clipper 29. The output of the latter is fed to a low pass filter 30 and then to an equalizing amplifier 31 whose output acts on the demodulator 17.

Demodulator 17 performs as follows:

If the inverted speech band is designated by the symbol Ei and if the symbol ω_0 is defined by the equation $\omega_0 = 2\pi 800$ the plurality of oscillations acting on the input of demodulator 17 will have the following analytical form:

$$Ei \sin(\omega_0 t + \psi v)$$

wherein ψv is the variable (jumping up and down) phase.

Selector 28 provides a phase varied oscillation of 800 cycles whose expression is:

$$\sin(\omega_0 t + \psi v)$$

This phase varied oscillation is transformed by

the clipper 29 and the low pass filter 30 into the sequence:

$$\sin(\omega_0 t + \psi v) + \frac{1}{3} \sin 3(\omega_0 t + \psi v) + \frac{1}{5} \sin 5(\omega_0 t + \psi v) + \frac{1}{7} \sin 7(\omega_0 t + \psi v)$$

The angle ψv can have only two values: zero degree and 90 degrees.

During all the intervals of time when $\psi v = 0$ the output of l. p. filter 30 has the form:

$$\sin \omega_0 t + \frac{1}{3} \sin 3\omega_0 t + \frac{1}{5} \sin 5\omega_0 t + \frac{1}{7} \sin 7\omega_0 t$$

During all the intervals of time when $\psi v = 90^\circ$ the output of 30 is expressed as follows:

$$\sin(\omega_0 t + 90^\circ) - \frac{1}{3} \sin(3\omega_0 t + 90^\circ) + \frac{1}{5} \sin(5\omega_0 t + 90^\circ) - \frac{1}{7} \sin(7\omega_0 t + 90^\circ)$$

The amplifier 31 equalizes the amplitudes of the terms of the "distorting" sequence.

It is easy to design the coil inserted in the plate circuit of said amplifier in such a way, that the harmonics remain in phase with the fundamental as it appears in the output of selector 18.

Under those conditions the output of demodulator 17 has alternately the form:

$$Ei \sin \omega_0 t (\sin \omega_0 t + \sin 3\omega_0 t + \sin 5\omega_0 t + \sin 7\omega_0 t)$$

and the forms

$$Ei \sin(\omega_0 t + 90^\circ) [\sin(\omega_0 t + 90^\circ) - \sin(3\omega_0 t + 90^\circ) + \sin(5\omega_0 t + 90^\circ) - \sin(7\omega_0 t + 90^\circ)]$$

In both cases the final result will be

$$\frac{1}{2} Ei - \frac{1}{2} Ei \cos 8\omega_0 t$$

$$\text{As } 8\omega_0 = 2\pi 6400$$

the l. p. filter 31 having its cut off at 3000 cycles will obviously eliminate the term

$$\frac{1}{2} Ei \cos 8\omega_0 t$$

so that only the inverted speech band Ei will be maintained.

It will be understood that various features and principles of each of the embodiments of the invention above described or referred to may be utilized or substituted in the other embodiments.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A method for secret electrical transmission of intelligence consisting in modulating the original speech-band, by a sequence of harmonically related oscillations having different frequencies for distorting the speech and to render the speech completely unintelligible, and in re-establishing intelligibility at the reception end, by modulating the distorted speechband by the fundamental of the said distorting sequence of harmonically related frequencies, taken in a particular phase relationship, whereby the sequence of several modulating frequencies is transformed into a single modulating frequency.
2. A method of secret transmission of intelligence which consists in inverting speechband and in modulating the inverted speechband by a sequence of harmonically related oscillations having such frequencies as to distort the in-

verted speech, and in reestablishing intelligibility by modulating the transmitted inverted and distorted speech by the fundamental of said distorting sequence of harmonically related frequencies used in a particular phase relationship, whereby the sequence of several modulating frequencies is transformed into a single modulating frequency, and reinverting the inverted speech.

3. A method of secret transmission of intelligence, consisting in inverting a speechband and in modulating this inverted speechband by a sequence of harmonically related phase varied oscillations having different frequencies, and reestablishing intelligibility by modulating the transmitted inverted and distorted speech by the fundamental of said distorting sequence of harmonically related phase varied oscillations, the fundamental being used in a proper phase relationship after having been subjected to the same phase variations as those of the distorting modulating oscillations, whereby the sequence of several modulating phase varied frequencies is transformed into a single modulating frequency.

4. A method of secret transmission of intelligence, consisting in inverting a speechband by a phase varied inverting oscillation, modulating this inverted phase varied speechband by a sequence of harmonically related oscillations, and reestablishing intelligibility by modulating the inverted and distorted speechband with a corresponding chosen oscillation undergoing phase variations and by performing the reinversion of the inverted speechband by a reinverting oscillation.

5. In a method of producing secret transmission of intelligence the steps which include producing a sequence of harmonically related frequencies located in the voice spectrum below the upper limit of the speech band used; and modulating a speech band by said sequence thereby rendering the speech unintelligible.

6. A method of secret transmission of intelligence, consisting in producing a sequence of harmonically related frequencies; modulating a speech band by said sequence thereby rendering the speech unintelligible; and reestablishing the intelligibility of the speech by producing a fundamental of the distorting sequence of frequencies by modulating with said fundamental the distorted speech, thereby obtaining a single modulating frequency.

7. In a method of producing secret transmission of intelligence the steps which include producing a sequence of harmonically related frequencies; equalizing the amplitudes of said frequencies; and modulating a speech band by the said sequence thereby rendering the speech unintelligible.

8. In a method of producing secret transmission of intelligence the steps which include producing a sequence of harmonically related frequencies; equalizing the amplitudes of said frequencies; periodically shifting the phase of the sequence; and modulating a speech band by said sequence thereby rendering the speech unintelligible.

9. In a method of producing secret transmission of intelligence the steps which include producing a sequence of harmonically related frequencies; equalizing the amplitudes of said frequencies producing a synchronizing frequency; periodically shifting the phase of the sequence by the synchronizing frequency; and modulating a speech band by the sequence thereby rendering the speech unintelligible.

10. In a method of producing secret transmission of intelligence the steps which include producing a sequence of harmonically related frequencies by submitting a low frequency oscillation to a shape distorting operation for changing the shape of the wave in such a manner as to produce harmonics having relatively strong amplitudes; and modulating a speech band by said sequence.

11. In a method of producing secret transmission of intelligence the steps which include producing a sequence of harmonically related frequencies located within the signal band in the voice spectrum used below the upper end thereof; inverting the speech band; and modulating the inverted speech band by said sequence.

12. A method of secret transmission of intelligence, consisting in producing a sequence of harmonically related frequencies producing a synchronizing oscillation; periodically shifting the phase of the sequence by the synchronizing oscillation; modulating the speech band by the sequence for rendering the speech unintelligible; transmitting the modulated speech band with the synchronizing oscillation; producing a fundamental of the distorting sequence of frequencies by displacing the phases of the harmonically related frequencies by the transmitted synchronizing frequency; and modulating the

distorted speech band by the fundamental frequency, thereby reestablishing the intelligibility of the speech.

13. An apparatus for secret communication, comprising means to transform speech into speech band frequencies; means to produce a sequence of harmonically related oscillations having different frequencies; means to modulate the speech band by the sequence; means to transmit the modulated frequencies by radio; means to receive and to detect the distorted transmitted speech band; means to produce a fundamental of the distorting sequence; means to transform the distorting modulation of the speech band produced by the sequence of modulated frequencies into a single modulating frequency; and means to modulate the distorted speech band by the fundamental of the distorting sequence thereby reestablishing the intelligibility of the speech.

14. An apparatus for secret communication, comprising means to transform speech into speech band frequencies; means to produce a sequence of harmonically related oscillations having different frequencies; means to change the phase relationship of the sequence; means to modulate the speech band by the sequence; means to transmit the modulated frequencies by radio; means to receive and to detect the transmitted distorted speech band; means to produce a fundamental of the distorting sequence in the same phase relationship for transforming the fundamental of the distorting sequence into a single modulating frequency; and means to modulate the distorted frequencies thereby reestablishing the intelligibility of the speech.

15. An apparatus for secret communication, comprising means to transform speech into speech band frequencies; means to produce a sequence of harmonically related oscillations having different frequencies; means to produce a synchronizing frequency; means to change the phase relationship of the sequence by the synchronizing frequency; means to modulate the speech band by the sequence; means to transmit and to detect the distorted speech band;

means to produce a fundamental of the distorting sequence in the phase relationship as controlled by the transmitted synchronizing frequency for transforming the fundamental of the distorting sequence into a single modulating frequency; and means to modulate the distorting frequencies thereby reestablishing the intelligibility of the speech.
